UNITED STATES PATENT OFFICE.

WILLIAM F. GATEWOOD, OF PIERCE CITY, MISSOURI, ASSIGNOR TO SIMPLEX ADDING MACHINE COMPANY, OF SAN ANTONIO, TEXAS, A CORPORATION OF DELAWARE.

ADDING-MACHINE.

1,123,515.

Specification of Letters Patent. Patented Jan. 5, 1915.

Application filed April 10, 1913. Serial No. 760,153.

To all whom it may concern:

Be it known that I, WILLIAM F. GATEWOOD, a citizen of the United States, residing at Pierce City, Missouri, have invented 5 a certain new and useful Improvement in Adding-Machines, of which the following is a full, clear, and exact description, such as will enable others skilled in the art to which it appertains to make and use the same, reference being had to the accompanying drawings, forming part of this specification, in which—

Figure 1 is a perspective view of an adding machine of my improved construction. 15 Fig. 2 is a plan view of the machine with the housing or casing removed. Fig. 3 is an enlarged sectional view taken approximately on the line 3—3 of Fig. 2. Fig. 4 is a detail section taken approximately on the line 20 4—4 of Fig. 3. Fig. 5 is a detail section taken approximately on the line 5—5 of Fig. 2. Fig. 6 is a plan view partly in section of parts which are arranged transversely beneath the center of the disk of my 25 improved machine, which parts are for the purpose of returning the main disk and the secondary disk to their original positions. Fig. 7 is a side elevational view of the parts seen in Fig. 6. Fig. 8 is a detail sectional view taken through the upper portion of 30 the shaft which carries the primary disk and showing a portion of the spring-actuated disk-moving finger.

My invention relates to new and useful 35 improvements in adding machines of the type shown and described in the patent issued to me May 9, 1903, No. 789,688.

The principal objects of my present invention are,—to provide a machine of simple and economical construction which can 40 be readily used for accurately and quickly adding up columns of figures; to provide a novel form of adding machine having a revoluble disk combined with a series of 45 keys in such a manner that the actuation of any key will shift the disk a distance corresponding to the position of the actuated key; to provide simple means whereby the disk is positively moved the proper distance 50 by the actuation of one of the keys; to provide simple means for controlling the movement imparted to the disk and preventing over-rotation thereof; to provide means for effectively locking the disk against movement in either direction while the same is

at rest; to provide a novel arrangement of transfer mechanism, whereby the movement of the main disk is transmitted to an auxiliary or secondary disk for designating a higher order of numbers; to provide simple 60 key-actuated means for zeroizing the main and auxiliary disks, and finally, to generally improve and simplify the construction of the adding machine disclosed in my patent hereinbefore referred to. 65

With the above and other objects in view, my invention consists in certain novel features of construction and arrangement of parts hereinafter more fully described and claimed. 70

The operating parts of my improved adding machine are mounted on a suitable base 10 of wood or metal, and arranged above the rear portion of this base and parallel therewith is a transversely disposed plate 75 11, the ends 12^a of which are extended downward and fixed to the base near its sides in any suitable manner.

Journalized in suitable bearings formed in the base 10 and in the center of the plate 11 80 is a vertically disposed shaft 12, and fixed thereto and occupying a position immediately beneath the plate 11 is a disk 13 provided near its edge with a row of apertures 14, the lower ends of which are countersunk 85 and on top of said disk these apertures are numbered from "00" to "99" inclusive.

Arranged on the base a short distance in front of the shaft 12 and concentric therewith is an arcuate block 15, from which 90 projects upwardly a series of radially arranged plates 16. Fulcrumed to the forward ends of these plates is a series of key levers 17, the forward ends of which bear numbered disks 18. In the present instance 95 I have shown 18 of these keys, and the numbers on the disks run from "1" to "18," with the odd numbers in one row and the even numbers in another row, but it will be readily understood that a greater or less 100 number of keys can be utilized if desired.

By providing keys higher than "9" it is possible to rapidly add in the machine with one operation two or more combinations of lower numbers, as, for instance, three "6"'s 105 or two "9"'s can be added by depressing the "18" key, or two "8"'s may be introduced by depressing the "16" key.

The forward ends of the key levers 17 project beyond the rear end of the block 15,

and connected to the rear end of each lever is a short retractile coil spring 19, the lower end of which is connected to the base 10.

Fixed to the ends of the arcuate block 15 are standards 20, and pivotally mounted therein are the forward ends of arms 21 which are radially arranged with respect to the shaft 12, and the forward ends of these arms are connected by an arcuate bar 22 which occupies a position immediately over the rear ends of the key levers 17.

Loosely mounted upon the upper end of the shaft 12 and supported by a collar 23 which is fixed to said shaft 12 is a grooved collar 24, to which is fixed one end of a disk-actuating arm 25, the opposite end of which is provided with a loop 26 which is loosely mounted upon the arcuate bar 22. Fixed to this arm 25 is an upwardly projecting pin 27 which is adapted to engage in any one of the apertures 14 in the disk 13. Connected to the arm 25 and occupying a portion of the grooved collar 24 is one end of a retractile coil spring 28, the opposite end of which is attached to one of the downwardly bent ends 12^a of the plate 11. This spring normally holds the arm 25 in position with the loop 26 at the left hand end of the arcuate bar 22.

30 A standard 29 is fixed to the base 10 near the left hand end of the block 15, and pivotally mounted on the upper portion of said standard is a detent 30 provided in its upper edge with a notch 31. This notch is normally occupied by the forward portion of the arm 25, and the upper edge of this detent in front of this notch is inclined, as designated by 32, so as to permit the arm 25 to readily return to its normal position in the 35 notch 31 after said arm has been actuated to move the disk. The end of the detent 30 opposite the end provided with the notch 31 is weighted, as designated by 33, in order to maintain said detent in proper position.

35 Seated in a block on the base 10 immediately to the rear of the left hand end of the block 15 is a pin or screw 34, and loosely mounted thereon is the coiled portion 35 of a spring, the upright leg 36 of which is positioned immediately in front of the detent 30 behind the forward end of the arm 25. The horizontal leg 37 of this spring passes through an aperture formed in the lower end of a link 38, the upper end of which latter is pivotally connected to the left hand end of the arcuate bar 22.

Under normal conditions there is no tension in the spring just referred to, and the leg 36 thereof does not exert pressure upon the forward end of the arm 25, but when the arcuate bar 22 is elevated before an actuation of one of the key levers the link 38 is drawn upward, thereby drawing the free end of the horizontal leg 37 upward, and consequently storing power in said spring

before the forward end of the arm 25 has been elevated free or wholly out of the notch 31 in the detent 30.

Fixed to the left hand ends of the arcuate block 15 are vertically disposed posts 70 39 provided with projections 40 above and below the arms 21, and these projections form stops to limit the vertical movement of said arms and the arcuate bar 22.

Fixed on top of the standard 20 at the right hand end of the block 15 is a forwardly projecting spring arm 41 which overlies the edge of the disk 13, and carried by the forward end of this arm is a short, depending pin 42 which is adapted to engage in the apertures 14. This arrangement provides a yielding restraining pawl for holding the disk against movement in either direction and preventing over-rotation thereof. Depending from the spring arm 41 is a pin 41^a, which is adapted to be engaged by the bar 22 when the same is elevated.

Pivotedly mounted on the right hand end of the bar 22 is a spring-held arm 43, the end of which carries an upwardly projecting short conical pin 44 which is adapted to engage in one of the apertures 14 when the bar 22 has been elevated thereby acting as a restraining pawl to prevent movement of the disk in either direction and hold the same against over-rotation when the spring arm 41 is elevated. The spring which actuates this arm 43 normally forces the outer end of said arm upward, and thus when the arcuate bar 21 is actuated, the outer end of said arm 43 will strike against the disk 13 with the pin 44 in one of the apertures 14, and by reason of a yielding connection between said arm and said arcuate bar, said bar can move a short distance upward even after the end of the arm 43 is in contact with the disk 13 during which movement power will be stored in the spring connected to said arm.

Journalized in the base 10 and plate 11 immediately to the left of the disk 13 is a vertically disposed shaft 45, and carried by the upper end thereof is a disk 46 bearing on its upper surface the numbers from "1" to "9" inclusive, this disk representing the hundredths disk, for when the main disk 13 has been rotated one complete turn the smaller disk 46 is rotated one-tenth of a turn, thereby bringing the "1" into view to indicate that "100" has been added upon the machine.

Arranged upon the shaft 45 is a torsional spring 47, one end of which is fixed to said shaft and the other end to the base 10. This torsional spring is for the purpose of returning the disk 46 to its normal position. Depending from the disk 46, and arranged in a circular row are ten pins 48, one of which, designated by 48^a, is longer than the

others, and said longer pin occupies a position directly opposite the space between the "1" and "9" on the face of said disk. Arranged in the path of travel of the lower end of this longer pin 48 is a finger or detent 49 which is fixed to and depends from the underside of the plate 11. When the disk 46 has made one complete revolution, thereby indicating an addition of "900", the longer pin 48 will strike against the detent 49, thereby locking the machine against further movement. Projecting from the edge of the main disk 13 at a point between the double "00" and "99" is a short pin 50, which, when said main disk has made one complete revolution, engages the corresponding one of the pins 48 to move the disk 46 one-tenth of a complete revolution, thereby transferring "100" to the small disk 46. The edges of the disks 13 and 46 lie immediately adjacent each other, as shown in Figs. 2 and 7, and formed in the plate 11 immediately over said adjacent edges is an opening 51 through which the numbers on said disks may be observed.

The rotation of the disk 46 imparts winding movement to the spring 47, thereby storing power therein, and as said disk is rotated step by step, it is held against reverse rotary movement by a detent or pawl 52 in the form of a lever fulcrumed at its outer end to the plate 11 and provided on its inner end with a beveled edge 53. This pawl or detent is drawn toward the disk 46 by means of a small retractile coil spring 54, and formed in the edge of said pawl or detent is a shoulder 55 which is adapted to engage against any one of the pins 48.

The means for restoring the disks 13 and 46 to their normal positions will now be described.

Arranged to slide between suitable guides on the base 10 below the plate 11 is a bar 56, the left hand end of which carries a vertically disposed plate 57, the upper edge of which lies immediately beneath the underside of the disk 13. The left hand upper corner of this plate 57 normally bears against the beveled edge 53 of the pawl or detent 52. Positioned on top of the right hand portion of the bar 56 is a secondary bar 58, the right hand end of which is pivotally connected to said bar 56, and the right hand end of this secondary bar is provided with a transverse slot 59, through which passes a pin 60, the same being seated in the bar 56. The rear edge of the left hand portion of the bar 58 is provided with a series of rack teeth 61 which are adapted to engage the teeth of a pinion 62 formed on the lower portion of the shaft 12.

Formed integral with and projecting forwardly from the right hand portion of the bar 58 is an arm 63 which is adapted to slide beneath a guide 64 which is fixed to

and spaced apart from the base 10. A standard 65 projects upward from the base in front of the forward end of the arm 63, and pivotally mounted on this standard is a bell crank 66, the lower end of the long arm of which bears against the right hand side of the arm 63. The end of the short arm of this bell crank 66 has a pin and slot connection with a bell crank 67, which latter is fulcrumed on a suitable standard to the right hand end of the standard 65, and engaging the short arm of this bell crank 67 is the rear end of a key lever 68, which latter is fulcrumed on a suitable standard to the right of the block 15, and said key lever being provided on its forward end with a disk 69 which occupies a position immediately adjacent to the right hand disks 18. A retractile coil spring 70 is connected to the arm 63 and to the adjacent depending end 12 of the plate 11.

Fixed to and depending from the disk 13 a short distance from the edge thereof and adjacent to the projection 50 is a pin or lug 71, which, when the plate 57 is in normal position, just clears the upper left hand corner of said plate, but when this plate is shifted toward the left hand, its upper edge is in the path of travel of said pin or lug 71.

A housing or casing 72, preferably formed of sheet metal, incloses the disk 13, plate 11, block 15 and parts associated therewith, as seen in Fig. 1, said housing being provided with an opening 73 which is directly above the opening 51 so that the numbers on the disks can readily be observed. The front wall of the housing 72 is preferably curved so as to conform to the curvature of the block 15, and said front wall is vertically slotted to accommodate the key levers 17 and 68.

The operation of my improved machine is as follows: The operator engages and presses downward upon the disk 18 bearing the number which it is desired to add into the machine, and as the corresponding key lever is swung upon its fulcrum, the rear end of said lever is elevated, thereby engaging and elevating the arcuate bar 22. This bar must necessarily move a short distance upward to free the forward portion of the arm 25 from the notch 31, and as the arcuate bar is thus moved upward, the link 38 is drawn upward, thereby drawing the leg 37 of the spring upward, which operation stores power in said spring. The leg of this spring is, during this movement, bearing against the edge of the arm 25, but this arm is not released until it is wholly free from the notch 31. As the forward end of the arm 25 is drawn upward by the arcuate bar, the pin 27 carried by said arm engages in the corresponding one of the apertures 14, and when said arm is wholly free from the notch 130

31, it will be instantly and forcibly thrown toward the right hand by the power stored in the spring comprising the legs 36 and 37, and as the arm is thus moved, the disk 5 13 which is engaged by the pin 27 is carried around a distance corresponding to the key which has just been depressed. The depression of the forward end of the key brings the rear end of the lever of said key against the arcuate bar 22, and this rear end forms 10 a stop against which the loop 26 engages, thus limiting the movement of the arm 25 and the disk 13. As the arcuate bar 22 is elevated it strikes against the finger 41^a, thereby elevating the free end of the spring arm 41, and consequently withdrawing the pin 42 from the aperture in which it has 15 been seated. This movement takes place an instant prior to the release of the arm 25 20 from the notch 31, and just before the arcuate bar has reached its limit of upward movement the conical pin 44, carried by the spring-actuated arm 43, will engage in one of the apertures 14 in the disk 13, thereby 25 forming a restraining pawl to hold the disk against movement in either direction during the interim between the withdrawal of the pin 42 from one of the apertures 14 and the 30 release of arm 25. During the movement imparted to the disk by the spring acting upon the arm 25, the conical pin 44 rides against the underside of said disk and passes in succession from one aperture 14 to the next, which movement is possible for the 35 reason that the lower ends of the apertures are counter-sunk and the pin 44 which is carried upon the spring actuated arm 43 is conical, and therefore, will yield downward slightly during the travel from one aperture 40 to another. It will be understood that the manner of mounting the arm 43 on the arcuate bar permits said arcuate bar to move upwardly a short distance after the pin 44 has engaged in one of the apertures 14, and 45 further, that said arcuate bar on its return or downward movement can move a short distance, and the pin 44 will remain in engagement with one of the apertures in the disk, which action is brought about by the 50 spring connected to said arm 43. The pins 44 and 27 are of such relative lengths as that the pin 27 is disengaged from the disk 13 just prior to the disengagement of the pin 44 from said disk. Thus, when the arm 55 25 is returning to normal position the disk is held against movement in either direction by said pin 44. As soon as the pressure upon the depressed key is released, the corresponding spring 19 draws the rear end of 60 the actuated key downward, thereby permitting the arcuate bar to move downward to its normal position, and as this movement takes place, the link 38 is moved downward, thereby restoring the spring comprising the 65 legs 36 and 37 to its normal position. As the arcuate bar 22 drops to its normal position, the forward end of the arm 25 which is loosely connected to said bar is drawn downward, thereby withdrawing the pin 27 from the aperture in which it has been engaged, 70 and immediately thereafter the retractile coil spring 28 acts to return the arm to its normal position, and as it reaches the pawl or detent 30, it bears against the beveled edge 32 thereon, thereby swinging said pawl 75 or detent upon its pivot point until said arm passes into the notch 31. The weight 33 on the end of the pawl or detent restores the same to its normal position, thereby holding the arm 25 in readiness for the next operation. The retractile coil spring 28 is comparatively light, and the action of the spring comprising the legs 36 and 37 overcomes the resistance offered by said spring 28 when an actuation of the parts just described takes place. 80

It will be understood that the movements just described take place very rapidly and in regular sequence, and an operator with little practice can very rapidly add up a column of figures by merely pressing the proper keys. The operator by mentally noting combinations of several figures, can do away with the necessity of striking keys corresponding to all of the figures, for, if it is desired to add into the machine two "6"'s 90 the operator can accomplish this by striking the "12" key, or to add two "7"'s the operation can be accomplished by striking the "14" key. As the various keys are depressed to add in the various numbers, the disk 13 is rotated step by step, and when the total has reached "99" the next movement imparted to the main disk brings the lug or projection 50 into engagement with one of the pins 48 on the disk 46, thereby moving said last mentioned disk one-tenth of a revolution and bringing the number "1" on said disk into view through the openings 51 and 73. 100

As hereinbefore stated, the disk 46 is held against reverse rotation by the engagement of one of the pins 48 against the shoulder 55 of the spring-held pawl or detent 52. After a column has been added up and it is 105 desired to restore the disks 46 and 13 to their normal positions, the operator presses the key 69, thereby moving the lever 68 upon its fulcrum and consequently actuating the bell crank 67. This bell crank in turn actuates the bell crank 66, and the lower end of the long arm thereof bears against the arm 63 and moves the same toward the left hand against the resistance offered by the retractile spring 70. 110

The upper left hand edge of the plate 57 normally bears against the beveled end 53 of the pawl or detent 52 so that the initial movement imparted to the bars 56 and 58 toward the left hand actuates the detent or 115 120 125 130

pawl 52 in such a manner as to withdraw the shoulder 55 from in front of the pin positioned against said shoulder, and the torsional action of the spring 47 will impart 5 partial rotary movement to the shaft 45 and the disk 46 carried thereby, thus rotating said disk to its normal position. The pressure of the long arm of the bell crank 66 against the arm 63 swings the bar 58 upon 10 its point of pivotal connection with the bar 56, thereby moving the left hand end of said bar 58 rearwardly a slight distance so that as this releasing movement continues and the bars 56 and 58 slide toward the left 15 hand, the rack teeth 61 on the bar 58 will engage the teeth of the pinion 62, thereby imparting rotary motion to the same, the shaft 12 and the disk 13 carried thereby. The force of this restoring movement overcomes 20 the restraining pressure exerted by the spring arm 41 carrying the pin 42, and as the bar 58 moves transversely, the disk is returned to its normal position with the double "00" positioned immediately beneath the 25 openings 51 and 73. As the bar 56 moves toward the left hand, the upper edge of the plate 57 is moved into the path of travel of the depending lug or pin 71, and as the disk 13 is rotated back to its normal position, this 30 lug or pin 71 strikes against the upper edge of the plate 57, thus stopping the disk at the proper point. As the pressure upon the key 69 is removed, the retractile spring 70 restores the bars 56 and 58 and other parts of 35 the mechanism just described to their normal positions.

A machine of my improved construction is comparatively simple in construction and operation, can be very rapidly operated, is 40 very compact, can be manufactured at comparatively little cost owing to the absence of complicated parts, and can be advantageously used wherever it is desired to quickly and accurately add single columns of figures.

It will be readily understood that minor changes in the size, form and construction of the various parts of my improved adding machine can be made and substituted for 50 those herein shown and described without departing from the spirit of my invention, the scope of which is set forth in the appended claims.

I claim:

55 1. In an adding machine provided with a rotating disk and its operating mechanism, which operating mechanism includes a pivotally mounted arm and a key-operated bar with which said arm co-operates, a spring 60 for imparting movement to said arm, which spring is put under tension by movement of the key-operated bar, means for holding the arm against movement while tension is being imparted to the spring, and means for

holding the disk against movement while 65 tension is being imparted to the spring.

2. In an adding machine provided with a rotating disk and its operating mechanism, which operating mechanism includes a pivotally mounted arm and a key-operated bar 70 with which the pivotally mounted arm co-operates, a spring for imparting movement to the pivoted arm, which spring is put under tension by the movement of the key-operated bar, means for holding the arm 75 against movement while tension is being imparted to the spring, and means adapted to be released by the upward movement of the key-operated bar for holding the disk against movement during the time tension 80 is being imparted to the spring.

3. In an adding machine provided with a rotating disk and its operating mechanism which operating mechanism includes a pivotally mounted arm and a key operated bar 85 co-operating with said arm, a spring for imparting movement to the pivotally mounted arm, which spring is put under tension by the initial movement of the key actuated bar, means for holding the pivotally mounted 90 arm while tension is being imparted to the spring, and a spring directly connected to said arm for returning the same to normal position after movement.

4. In an adding machine provided with 95 a rotating disk and its operating mechanism, which operating mechanism includes a pivotally mounted arm and a key operated bar co-operating with said arm, a spring for imparting movement to the pivotally mounted 100 arm, which spring is put under tension by the initial movement of the key actuated bar, means for holding the pivotally mounted arm while tension is being imparted to the spring, a spring directly connected to 105 said arm for returning the same to normal position after movement, and means for holding the disk against movement while tension is being imparted to the spring.

5. In an adding machine of the class described, a rotatable numeral-bearing disk, a second revolute numeral-bearing disk adapted to be partially rotated by the first mentioned disk as the same is completely rotated, a spring connected to the second 115 mentioned disk so that power is stored therein when said disk is rotated, spring-held means for holding the second mentioned disk against reverse movement, and a key-actuated means for releasing the spring- 120 pressed means to permit the second mentioned disk to return to its normal position, and which key-actuated means engages directly with the axis of the first mentioned disk to return the same to its normal or 125 zero position.

6. In a machine of the class described, a rotatable numeral-bearing disk, means in-

cluding a series of key levers for imparting movement to said disk, a pin depending from said disk, key-operated mechanism, a portion of which engages directly with the 5 axis of the disk for restoring the same to its normal or zero position, and a plate on said key-operated means, which plate is moved into the path of travel of the pin carried by the disk to form a stop for the reverse move-
10 ment of said disk.

7. In an adding machine, provided with a vertically disposed shaft, a pinion thereon, a numeral-bearing disk carried by said shaft, and means including a series of key 15 levers for imparting movement to said disk, a sliding plate, a rack bar pivotally mounted on said sliding plate, and normally out of engagement with the pinion, key-operated means for moving said rack bar into 20 engagement with the pinion and then actuating said sliding plate, and rack bar to effect rotation of the shaft and parts carried thereby.

8. In an adding machine, provided with a vertically disposed shaft, a pinion thereon, 25 a numeral-bearing disk carried by said shaft, and means including a series of key levers for imparting movement to said disk, a sliding plate, a rack bar pivotally mounted on said sliding plate and normally out of 30 engagement with the pinion, key-operated means for moving said rack bar into engagement with the pinion and then actuating said rack bar to effect rotation of the shaft and parts carried thereby, and sliding 35 plate means for stopping the reverse rotary movement of the disk at a predetermined point.

In testimony whereof I hereunto affix my signature in the presence of two witnesses, 40 this 1st day of April, 1913.

WILLIAM F. GATEWOOD.
